UNITED STATES PATENT OFFICE.

WILLIS H. CARRIER, OF NEW YORK, N. Y., ASSIGNOR TO CARRIER ENGINEERING CORPORATION, OF NEW YORK, N. Y.

REFRIGERATING SYSTEM.

Application filed February 2, 1921. Serial No. 441,876.

To all whom it may concern:

Be it known that I, WILLIS H. CARRIER, a citizen of the United States, residing at New York, in the county of New York and 5 State of New York, have invented a new and useful Improvement in Refrigerating Systems, of which the following is a specification.

This invention relates to refrigerating 10 systems of the compression type in which a volatile refrigerant liquid is boiled or evaporated in an evaporator by the heat abstracted from the substance being cooled, and the vapor of the refrigerant is with- 15 drawn from the evaporator and delivered by a compressor at a higher pressure to a condenser in which the vapor is condensed, after which the liquefied refrigerant is returned to the evaporator. The most common 20 systems of this kind are those using ammonia as the volatile working substance, but there are numerous recognized objections to the ammonia systems. Ammonia requires high pressures, necessitating heavy, 25 cumbersome, iron or steel apparatus, large reciprocating or positive compressors, and cumbersome power-operated control devices, and on account of the poisonous nature of the substance, a leak in the system 30 is very dangerous, so that expensive and special precautions and apparatus are necessary to reduce to the minimum the possibility of leaks and the danger therefrom.

One of the objects of the invention is to 35 provide a practical, efficient, and safe refrigerating or cooling system which is constructed and operates in a novel manner, whereby many of the objections to known systems are obviated and certain desirable 40 results are attained which are not possible with the refrigerating systems heretofore used. Another object is to construct the apparatus so that it can be set or adjusted to reduce the temperature of the substance 45 being cooled to a predetermined desired degree and will operate automatically to prevent a lower temperature of the substance, and thus preclude the possibility of freezing and injury to the apparatus.

50 Other objects of the invention are to withdraw the vapor of the refrigerant from the evaporator and deliver it at the required higher pressure to the condenser by means of a centrifugal or non-positive type of refrigerant is vaporized or boiled, B a con-

compressor, which will give the pressure 55 necessary for the desired operation of the apparatus but will fail to produce more than the desired maximum pressure, and thus operate automatically to determine the degree of refrigeration; also to employ a centrifugal or non-positive type of compressor which can be driven at a constant speed and produce a constant temperature irrespective of the volume of the vapor being handled, and whereby the degree of refrigeration can be 60 fixed by the speed at which the compressor is driven; also to regulate the temperature or pressure in the condenser under the control of the temperature of the liquid or material being cooled; also to regulate the 65 temperature of the compressed vapor delivered from the compressor automatically through the medium of a portion of the refrigerant liquid which is returned to the compressor and is evaporated therein to 70 lower the temperature of the compressed vapor when this becomes necessary; also to produce an efficient evaporator of novel construction; and also to improve refrigerating 75 systems in the other respects hereinafter 80 described and set forth in the claims.

In the accompanying drawings:—

Fig. 1 is a diagrammatic elevation of a refrigerating system embodying the invention.

Fig. 2 is an enlarged sectional elevation of the evaporator.

Fig. 3 is a fragmentary sectional elevation thereof on a still larger scale.

Fig. 4 is a fragmentary transverse section thereof on line 4—4, Fig. 3.

Fig. 5 is an enlarged sectional elevation of the condenser and the controlling devices therefor.

Fig. 6 is an enlarged sectional plan view 95 thereof on line 6—6, Fig. 5.

Fig. 7 is an enlarged sectional elevation of the compressor and separator for the vapor and compressor sealing liquid.

Fig. 8 is an enlarged sectional plan view 100 of the thermostatic trap or device for controlling the temperature of the compressed vapor.

Fig. 9 is a similar view showing a thermostatic trap or device of slightly modified construction.

A represents an evaporator in which the refrigerant is vaporized or boiled, B a con-

denser for the vapor, and C a pump or compressor which withdraws the vapor of the refrigerant from the evaporator and delivers it under pressure to the condenser.

3 The liquid or substance to be cooled is circulated through the evaporator in which there is an interchange of heat between this liquid and the liquid refrigerant, which evaporates or boils the refrigerant liquid.

10 The compressor, as usual, maintains an absolute pressure in the evaporator sufficiently lower than in the condenser to cause the evaporation of the volatile refrigerant at a temperature low enough to give the desired 70

15 temperature reduction of the liquid or substance being cooled. The condensed or liquefied refrigerant is returned from the condenser to the evaporator to be again evaporated. The invention is susceptible of embodiment in apparatus of various different 75

20 constructions and various different volatile liquids, such as ethyl chloride, methyl chloride, sulphur dioxide or carbon tetrachloride, can be used for the refrigerating medium, the construction of the apparatus and 80

25 the selection of the refrigerant depending more or less upon the conditions to be met and the capacity required. In this application one of the possible embodiments of the 85

30 invention is shown and described. This apparatus is designed more particularly to cool water to a temperature slightly above the freezing point, for example, from 33° F. to 35° F. for use afterwards in dehumidifying air, and water at natural temperatures, such as supplied by the usual city 90

35 service systems, can be used in the condenser for condensing the vapor. Ethyl chloride is preferably used for the volatile 95

40 refrigerating medium, because it is non-poisonous and enables the system to be operated at moderate pressures. The system herein described requires only a difference of about 20 to 25 pounds pressure between 100

45 the evaporator and the condenser. Ethyl chloride is also inert and permits the use of brass in the apparatus and this is desirable because brass gives a rapid exchange of temperatures and ordinary brass fittings 105

50 and control devices can be used. This invention is not, however, restricted in application to systems for the purpose stated and other suitable volatile liquids can be 110

55 used as the refrigerant. The system can also be used for cooling fluids other than water, and for other cooling purposes, and any suitable fluid can be used for cooling the vapor in the condenser. 115

The evaporator A shown (see Figs. 2-4), 120

60 comprises an outer cylinder or casing 20 which is provided at its upper end with a hollow head 21 connected by a series of tubes 22 with a hollow head or chamber 23 loosely or movably arranged in the lower 125

65 end of the casing. The upper head shown 130

is divided into three chambers and the lower head is divided into two chambers. The water or liquid to be cooled is admitted by a supply pipe 24 to one chamber of the upper head 21, flows downwardly through some of the tubes 22 into one chamber of the lower head, thence upwardly through other water tubes into the central chamber of the upper head, down again through other water tubes to the other chamber of the lower head and thence up again to the discharge chamber of the upper head from which the water discharges through a discharge pipe 25. The water flow tubes 22 are surrounded between the upper and lower hollow heads by tubes 26 which are open at their upper and lower ends and form around each of the water tubes 22 a narrow annular flow space for the refrigerant liquid and vapor. The casing of the evaporator is partially filled to a desired predetermined level with the liquid refrigerant X which thus surrounds the lower portions of the water and refrigerant flow tubes. The water or liquid to be cooled flowing through the evaporator gives up heat to the refrigerant and causes the latter to evaporate or boil. The refrigerant liquid and vapor boil over or discharge out of the upper ends of the outer tubes 26, producing an active, upward circulation of the liquid and vapor through the outer tubes, which sweeps or washes the bubbles of vapor off of the surfaces of the tubes and keeps the surfaces clean and wet with films of refrigerant liquid. This increases the transmission of the heat through the walls of the tubes and the efficiency of the evaporator. The evaporator is preferably placed at an inclination as shown. One of the chief purposes in this design of evaporator is to use a relatively small body of liquid and a low liquid level over the tubes. This method of evaporation permits the tubes to be very slightly submerged, and have a very low liquid pressure on them so that the evaporation is rapid. This is one of the chief difficulties with low pressure systems such as the ethyl chloride and on relatively large evaporating surfaces, it is impossible to use efficiently the ordinary submerged tubes such as used with ammonia. Every foot of submergence means an increase in vapor pressure of 1" of mercury with corresponding increase of temperature, which, with ethyl chloride, amounts to several degrees, while with ammonia it is very slight. 130

The vapor is withdrawn from the upper portion of the evaporator through a pipe 27 connecting with the intake of the vapor pump or compressor C which compresses and discharges the vapor through a discharge pipe 28 leading to the upper end of the condenser B. The condenser B, see Figs. 5 and 6, pref-

erably comprises an outer cylinder or casing 30 provided at its upper end with a hollow head 31 which is connected by flow tubes 32 with a hollow head 33 loosely or movably arranged in the lower portion of the casing. The upper and lower hollow heads, as in the case of the evaporator, are preferably divided into chambers so that the cooling water or liquid admitted by a pipe 34 to the upper head circulates up and down through the tubes and chambers of the heads and is discharged from the last chamber of the upper head through a pipe 35. The condenser is also preferably provided with partitions or baffle plates 36 extending alternately from opposite heads of the condenser lengthwise between the flow tubes so as to cause the vapor which is admitted into the upper portion of the outer casing to flow up and down in the condenser casing around the partitions and thus have an extended, intimate contact with the flow tubes. The lower end of the condenser cylinder or casing is connected by a return pipe 37 to the lower portion of the casing of the evaporator for returning the condensed or liquefied refrigerant from the condenser to the evaporator. A check valve 38 is shown in this pipe to prevent back flow to the condenser, and the discharge of the refrigerant liquid from the condenser is controlled by a suitable trap 39 which, as shown, consists of a float-operated valve that acts to retain a substantially constant quantity of the liquid refrigerant in the bottom of the condenser casing. This valve need not seat tightly and normally remains partly open. A strainer 40 of fine mesh wire, chamois or other suitable material can enclose the valve 39 if desired to prevent any water in the condenser from being returned to the evaporator. 41 represents a refrigerant supply pipe connecting with the return pipe 37 and provided with a suitable hand valve 42. The evaporator can be filled to the desired level with the refrigerant through this supply pipe.

The compressor C is of a centrifugal or non-positive type. A hydro-turbine compressor of known construction is shown, see Fig. 7, comprising an elliptical casing in which revolves a rotor 45 provided with a plurality of projecting blades 46. A sealing liquid revolves with the rotor but follows the elliptical casing, due to centrifugal force and twice in each revolution of the rotor the sealing liquid alternately recedes and reenters the pockets or spaces between the blades of the rotor. At points at the side of the casing where the sealing liquid is moving outwardly, inlet ports 47 are connected to the vapor inlet pipe 27. Similar outlet ports 48 connected to the discharge pipe 28 are located in the sides of the casing at points where the liquid reenters the

rotor. As the sealing liquid recedes from the rotor, vapor is drawn in through the inlet ports to fill the void, and as the rotor advances the vapor contained between the surface of the sealing liquid and the hub 70 of the rotor is compressed by the reentering liquid and forced out through the outlet ports. As the blades of the rotor pass the end of the outlet ports all of the vapor has been expelled and the spaces between the 75 rotor blades are full of the sealing liquid ready to repeat the operation. The sealing liquid used for the compressor depends upon the nature of the liquid that is used as the refrigerant and is preferably selected with 80 a view to minimizing the absorption of the refrigerant. If ethyl chloride is used for the latter, mercury or water can be employed as the sealing liquid for the compressor, mercury being preferable for the 85 smaller installations. Sulphuric acid and glycerine are other liquids which can be used.

D represents a separator or device for separating from the vapor discharged by 90 the compressor any sealing liquid which may be discharged with the vapor. This separator may be of any suitable construction. As shown it comprises a casing provided with a suitable baffle 50 which prevents a direct flow of the vapor through the casing from inlet to outlet. The vapor strikes the baffle which throws the moisture down, causing the sealing liquid to accumulate in the lower portion of the casing while 100 the vapor can pass around the edges of the baffle. A pipe 51 leads from the lower end of the discharge chamber 52 of the separator to a tank or reservoir 53 for the sealing liquid and this tank connects by 105 a supply pipe 54 with the vapor inlet pipe or intake of the compressor. The discharge pipe 51 of the separator is preferably controlled by a float-actuated valve which maintains a liquid seal in the bottom of 110 the separator. 55 represents a pressure relief pipe connecting the upper portion of the tank 53 with the inlet or suction pipe of the compressor. 56 represents a branched pipe leading from the bottom of the 115 separator to the stuffing boxes for the rotor of the compressor for sealing these stuffing boxes or glands.

The difference in pressure in the evaporator and in the condenser depends upon 120 the speed of rotation of the compressor and the centrifugal force produced since the compressor described cannot give more than a definite known vacuum at a given speed or rotation. A greater vacuum would break the liquid seal in the compressor. Therefore, the pressures in the evaporator and condenser can be fixed as desired within the limits of the compressor by driving 125 the compressor at the appropriate speed 130

and the danger incident to a lower vacuum in the evaporator is avoided.

60—60^a represents a pipe by which refrigerant liquid with any of the sealing liquid contained therein can be returned from the condenser to the compressor for regulating the temperature of the compressed vapor. This pipe leads from the lower end of the condenser and preferably 10 enters the side of the compressor at a point between the vapor inlet and outlet ports, such that the rotor of the compressor can draw the liquid from the condenser into the compressor. The admission of this liquid 15 to the compressor is controlled automatically by a trap or device E which, as shown in Fig. 8, comprises a valve 61 which is movable in a valve casing 62 interposed in the return pipe 60—60^a. When this valve 20 is opened the liquid can pass the same and enter the compressor and when the valve is closed it will stop the admission of the liquid. The valve is opened by a thermo-expansive element 63 preferably consisting 25 of an expansible chamber containing a volatile liquid, the vapor pressure of which changes with fluctuations in the temperature affecting the element. This thermo-responsive element is located in the separator casing D so as to respond to changes 30 in temperature therein. If the temperature increases above the desired maximum, preferably about 105° F., the thermo-responsive element will expand and open 35 the valve 61 permitting some of the refrigerant liquid to enter the compressor. The liquid will be vaporized by the heat in the compressor and this evaporation will cause a reduction in the temperature of the 40 vapor in the compressor and separator. The thermostatic-trap E thus acts to maintain a substantially constant, uniform 45 temperature of the compressed vapor. In addition to regulating the temperature of the compressed vapor this trap also serves to return to the compressor any water or sealing liquid which is carried with the vapor to the condenser, thereby preventing the water from accumulating in the refrigerant 50 circulating system.

Instead of using the described thermostatic trap, the water condensate can be trapped back to the compressor by means of a trap E' such as shown in Fig. 9. In 55 this trap the valve 61^a controls the flow of the refrigerant liquid through the pipe 60 as above explained, but the thermo-responsive element 63^a is enclosed in a casing 64 through which the refrigerant liquid passes from the valve chamber on 60 its way to the compressor. Water or other relatively non-volatile condensate will pass the valve freely, but when any appreciable quantity of volatile liquid passes the valve, 65 it will evaporate in chamber 64 and lower

the temperature, thus closing the valve 61^a and preventing further passage of the volatile liquid. Other suitable means for this purpose could also be used.

The temperature in the condenser B is 70 preferably regulated automatically by controlling the supply of the cooling water to the condenser, and since the vapor pressure in the condenser changes with the temperature, either a temperature or a 75 pressure actuated control device can be utilized. Preferably a thermostat F is used which extends into the upper part of the condenser and controls the flow of compressed air through a pipe 70 to the actuating diaphragm or motor of a valve G in the water supply pipe 34 of the condenser. If the desired maximum temperature in the condenser, preferably about 90° F., is exceeded the thermostat operates the valve 80 G to increase the supply of water which reduces the temperature in the condenser. The compressed air is preferably supplied by an air pump 72 which, for the reason hereinafter explained is connected to the 85 pump 73 that circulates the liquid to be cooled through the evaporator A, so that the air pump operates only when the liquid pump is running. Any other suitable means for regulating the temperature and 90 pressure in the condenser could be used.

H represents a thermostat which acts as a safety device to prevent the refrigeration of the liquid being cooled below a predetermined desired minimum temperature, for example, about 35° F. Preferably this thermostat is located in the cooled liquid discharge pipe 25 from the evaporator and controls the flow of compressed air from the air pump 72 through pipes 74 and 75 105 to the operating diaphragm or motor of a valve I in the water supply pipe 34 of the condenser. This valve is normally held open during the operation of the system by the air pressure from the air pump 72, but if the temperature of the cooled water falls below the minimum for which the thermostat H is set, this thermostat will act to reduce the air pressure and allow the valve I to close and stop the flow of water 110 to the condenser. This causes an increase in pressure of the compressed refrigerant vapor and breaks the liquid seal of the compressor, in this way reducing the vacuum 115 in the evaporator A and preventing further cooling of the cooled liquid.

Means are also shown whereby the thermostat H in the discharge pipe for the cooled liquid is adapted to stop or reduce the speed of the compressor when the thermostat acts as just explained to prevent the temperature in the evaporator falling below the minimum for which the thermostat is set. For this purpose the motor 80 which drives the compressor is provided with a 120 125 130

5 rheostat or speed controlling device 81
 adapted to be actuated by means of an air
 motor or diaphragm 82 operated by air pres-
 sure delivered thereto through a pipe 82
 under the control of the thermostat H.
 When the thermostat acts it will stop or
 slow down the compressor motor. This
 saves power and also provides an additional
 10 safeguard against the lowering of the tem-
 perature in the evaporator beyond a desired
 or safe point.

I claim as my invention:—

1. In a refrigerating system in which a
 volatile liquid refrigerant is employed, the
 15 combination of an evaporator in which the
 refrigerant liquid is adapted to vaporize,
 a condenser including means for condensing
 the refrigerant vapor, a compressor which
 withdraws the refrigerant vapor from the
 20 evaporator and delivers it to the condenser,
 said compressor being of a non-positive type
 adapted to produce a greater or less differ-
 ence in pressures in the evaporator and con-
 denser depending upon the speed of the com-
 25 pressor, and means responsive to the tem-
 perature produced in the evaporator for
 limiting the pressure difference produced by
 said compressor.

2. In a refrigerating system in which a
 30 volatile liquid refrigerant is employed, the
 combination of an evaporator in which the
 refrigerant liquid is adapted to vaporize, a
 condenser including means for condensing
 the refrigerant vapor, a compressor which
 35 withdraws the refrigerant vapor from the
 evaporator and delivers it to the condenser,
 said compressor being of a non-positive
 type adapted to produce a greater or less
 difference in pressures in the evaporator
 40 and condenser depending upon the speed of
 the compressor, and means responsive to the
 temperature produced in the evaporator for
 increasing the pressure in the condenser to
 limit the pressure difference produced by
 45 said compressor.

3. In a refrigerating system in which a
 volatile liquid refrigerant is employed, the
 combination of an evaporator in which the
 refrigerant liquid is adapted to vaporize,
 a condenser including means for condensing
 50 the refrigerant vapor, a compressor which
 withdraws the refrigerant vapor from the
 evaporator and delivers it to the condenser,
 said compressor being of a non-positive type
 adapted to produce a greater or less differ-
 55 ence in pressures in the evaporator and con-
 denser depending upon the speed of the com-
 pressor, and means responsive to the tem-
 perature produced in the evaporator for
 increasing the pressure in the condenser and
 60 reducing the speed of the compressor to
 limit the pressure difference produced by the
 compressor.

4. In a refrigerating system in which a
 65 volatile liquid refrigerant is employed, the

combination of an evaporator in which the
 refrigerant liquid is adapted to vaporize,
 a condenser including means for condensing
 the refrigerant vapor, a compressor which
 withdraws the refrigerant vapor from the
 70 evaporator and delivers it to the condenser,
 said compressor operating by centrifugal
 force to produce a difference in pressures
 in the evaporator and condenser that is
 greater or less depending upon the speed of
 75 rotation of the compressor, and means re-
 sponsive to the temperature produced in the
 evaporator for limiting the pressure differ-
 ence produced by said compressor.

5. In a refrigerating system in which a
 volatile liquid refrigerant is employed, the
 combination of an evaporator in which the
 refrigerant liquid is adapted to vaporize,
 a condenser including means for condensing
 80 the refrigerant vapor, a compressor which
 withdraws the refrigerant vapor from the
 evaporator and delivers it to the condenser,
 said compressor operating by centrifugal
 force to produce a difference in pressures in
 85 the evaporator and condenser that is greater
 or less depending upon the speed of rota-
 tion of the compressor, and automatic means
 governed by the temperature produced by
 the system for increasing the pressure in
 90 the condenser to limit the pressure differ-
 ence produced by said compressor.

6. In a refrigerating system in which a
 volatile liquid refrigerant is employed, the
 combination of an evaporator in which the
 refrigerant liquid is adapted to vaporize,
 a condenser including means for condensing
 100 the refrigerant vapor, a compressor which
 withdraws the refrigerant vapor from the
 evaporator and delivers it to the condenser,
 said compressor having means for propelling
 a body of sealing liquid and operating by
 105 centrifugal force to produce a difference in
 pressures in the evaporator and condenser
 which is dependent upon the speed of rota-
 tion of the compressor, and thermally con-
 trolled means for returning a regulated
 110 quantity of the refrigerant liquid to the
 compressor for effecting a controlled reduc-
 tion in the temperature of the compressed
 refrigerant vapor.

7. In a refrigerating system in which a
 volatile liquid refrigerant is employed, the
 combination of an evaporator in which the
 refrigerant liquid is adapted to vaporize,
 a condenser including means for condensing
 115 the refrigerant vapor, a compressor which
 withdraws the refrigerant vapor from the
 evaporator and delivers it to the condenser,
 said compressor having means for propelling
 a body of sealing liquid and operating by
 120 centrifugal force to produce a difference
 between the pressures in the evaporator and
 in the condenser which is dependent upon
 the speed of rotation of the compressor, and
 automatic means for returning a regulated
 125

quantity of the refrigerant liquid and sealing liquid from the condenser to the compressor for separating the sealing liquid from the refrigerant and for effecting a controlled reduction in the temperature of the compressed vapor.

8. In a refrigerating system in which a volatile liquid refrigerant is employed, the combination of an evaporator in which the refrigerant liquid is adapted to vaporize, a condenser including means for condensing the refrigerant vapor, a compressor which withdraws the refrigerant vapor from the evaporator and delivers it to the condenser, said compressor having means for propelling a body of sealing liquid and operating by centrifugal force to produce a difference in pressures in the evaporator and condenser which is dependent upon the speed of rotation of the compressor, and means controlled by the temperature of the compressed refrigerant vapor for returning a regulated quantity of refrigerant liquid to the compressor for maintaining a substantially constant temperature of the compressed refrigerant vapor.

9. In a refrigerating system in which a volatile liquid refrigerant is employed, the combination of an evaporator in which the refrigerant liquid is adapted to vaporize, a condenser including means for condensing the refrigerant vapor, a compressor which withdraws the refrigerant vapor from the evaporator and delivers it to the condenser, said compressor being of a non-positive type adapted to produce a greater or less difference in pressure in the evaporator and condenser depending upon the speed of the compressor, means for maintaining a substantially constant temperature and pressure in the condenser, and automatic means responsive to the temperature produced in the

evaporator for limiting the pressure difference produced by said compressor.

10. In a refrigerating system in which a volatile liquid refrigerant is employed, the combination of an evaporator in which the refrigerant liquid is adapted to vaporize, a condenser including means for condensing the refrigerant vapor, a compressor which withdraws the refrigerant vapor from the evaporator and delivers it to the condenser, said compressor being of a non-positive type adapted to produce a greater or less difference in pressures in the evaporator and condenser depending upon the speed of the compressor, automatic means responsive to temperature and pressure changes in the condenser for maintaining a substantially constant temperature and pressure in the condenser, and automatic means responsive to the temperature produced in the evaporator for limiting the pressure difference produced by said compressor.

11. In a refrigerating system in which a volatile liquid refrigerant is employed, the combination of an evaporator in which the refrigerant liquid is adapted to vaporize, a condenser including means for condensing the refrigerant vapor, a compressor which withdraws the refrigerant vapor from the evaporator and delivers it to the condenser, said compressor being of a non-positive type adapted to produce a greater or less difference between the pressures in the evaporator and in the condenser depending upon the speed of the compressor, means for driving said compressor at a substantially constant speed, and means responsive to temperature produced in the system operating to limit the pressure difference produced by said compressor.

WILLIS H. CARRIER.
